(57) **CLAIM**

The ornamental design for a scan pen, as shown and described.

DESCRIPTION

FIG. 1 is a perspective view of a scan pen showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dashed or broken lines shown in the drawings depict portions of the scan pen in which the design is embodied that form no part of the claimed design.

1 Claim, 7 Drawing Sheets
